(57) **CLAIM**

The ornamental design for remote controller for vehicle, as shown and described.

DESCRIPTION

FIG. 1 is a perspective view of remote controller for vehicle showing our new design;

FIG. 2 is a left side view of the remote controller for vehicle shown in solid lines;

FIG. 3 is a right side view of the remote controller for vehicle shown in solid lines;

FIG. 4 is a right side view of a controller body that the switch may be used in shown in phantom;

FIG. 5 is a top view of the remote controller for vehicle shown in solid lines;

FIG. 6 is a bottom view of the remote controller for vehicle shown in solid lines; and,

FIG. 7 is a top view of the remote controller switch shown in solid lines.

The vehicle controller switch to which the present design is applied is pressed to remotely control a given electronic device of the vehicle (such as a door lock) according to a mode of the pressed switch. The broken lines in the drawings illustrate the environment of the claimed design only and form no part of the claimed design.

1 Claim, 6 Drawing Sheets
